US0D1078973S

(12) **United States Design Patent** (10) **Patent No.:** **US D1,078,973 S**
(45) **Date of Patent:** **** Jun. 10, 2025**

(54) **DISPENSER**

(71) Applicant: **S.C. JOHNSON & SON, INC.**,
Racine, WI (US)

(72) Inventors: **Jesse Richard**, Racine, WI (US);
Michael Haynes, Muskego, WI (US);
David Dycher, Shenzhen (CN); **Harold Augier**, Zhongshan (CN)

(73) Assignee: **S. C. JOHNSON & SON, INC.**,
Racine, WI (US)

(**) Term: **15 Years**

(21) Appl. No.: **29/851,964**

(22) Filed: **Sep. 1, 2022**

(51) LOC (15) Cl. **23-04**

(52) U.S. Cl.

(57) **CLAIM**

The ornamental design for a dispenser, as shown and described.

DESCRIPTION

FIG. 1 is an isometric view of a top, front, and right side of an ornamental design for a dispenser;

FIG. 2 is an isometric view of a top, front, and left side of the dispenser of FIG. 1;

FIG. 3 is a front elevational view of the dispenser of FIG. 1;

FIG. 4 is a rear elevational view of the dispenser of FIG. 1;

FIG. 5 is a right side elevational view of the dispenser of FIG. 1;

FIG. 6 is a left side elevational view of the dispenser of FIG. 1;

FIG. 7 is a top plan view of the dispenser of FIG. 1; and,

FIG. 8 is a bottom plan view of the dispenser of FIG. 1.

The dash-dash-dash broken lines are included for the purpose of illustrating portions of the dispenser that form no part of the claimed design. The dash-dot-dash broken lines illustrate boundary lines and form no part of the claimed design.

1 Claim, 8 Drawing Sheets
